UNITED STATES PATENT OFFICE.

GEORG SPIESS, OF LEIPZIG-PLAGWITZ, GERMANY.

PNEUMATIC SHEET FEEDER.

Application filed July 18, 1927, Serial No. 206,654, and in Germany July 17, 1926.

It has become known for pneumatic sheet-feeders to control the suction-air by permanently rotating distributing rotary-valves. This presents the inconvenience, that in the 5 hollow-cylindrical or hollow-conical distributing valve casing the control-ports must be partly in the form of long slots whereby the wall of the distributing slide-valve is considerably weakened. When for the slots 10 a number of holes are substituted, the suction-effect becomes irregular this being prejudicial for the separating of the sheets. The greatest draw-back of the commonly used arrangements is however, that alteration 15 of the times at which controlling takes place is possible only by interchanging the control-valves so that consequently the workman who attends the machine, cannot regulate the control.

20 To avoid these inconveniences the distributing valves which liberate and shut-off the suction-and blowing-air, are controlled, according to the invention, by circulating cams. Bringing into register of the control-ports of the rotating valves with the 25 control-ports of the stationary valve housings takes place consequently in jerks, and these ports remain registering when the rotary valve is at rest, until by the next following cam the position is suddenly altered. The control-ports of the valves need to be, 30 therefore, only of small dimensions and the suction-or blowing-air is suddenly liberated and shut-off in full strength.

35 The control cams, which control the distributing valves for the suction-air and for the blowing-air are adjustably arranged so that the time, at which the blowing-or suction-air is shut off, can be altered at will.

40 This is specially advantageous as it might be necessary to make the suction-air and accordingly also, the blowing-air, enter into function sooner or later. The control cams are preferably adjustably arranged on a 45 common control-shaft and displaced in axial direction in such a manner that the control-cam for the suction-air cooperates only with the distributing valve for the suction-air, the control-cam for the blowing-air cooperating 50 only with the distributing valve for the blowing air. With this object in view the control-cams for the suction-air are respectively arranged on the front side and those for the blowing air on the rear side of a disk comprising fixation-and adjusting slots. On the same cam-shaft the driving

cam for the ratchet-feed gear of the stapling-mechanism is arranged.

The rotary valves for distributing the blowing air and suction-air are connected, 60 according to the invention, to a common blower which supplies the suction-and blowing air and is adapted to be brought by the valves into communication with the atmosphere, according to the requirements. 65 Rotary blowers have already been used in connection with pneumatic-sheet-feeding mechanisms, but either for the production of the suction air or for the production of the blowing air.

70 An embodiment of the invention is shown, by way of example, in the accompanying drawing in which:—

75 Fig. 1 shows the total arrangement in side elevation.

Fig. 2 shows on larger scale in longitudinal section a distributing slide valve.

80 Figs. 3 and 4 show each a cross section of the distributing slide valve in different positions.

85 Figs. 5 and 6 show respectively in elevation and in top plan view the arrangement of the control cams for the suction air and for the blowing air on a common control-shaft.

90 A rotary blower 2 driven from an engine 1 and being of any suitable construction serves for the production of the blowing air and suction-air. A suction-pipe 3 and a pressure-pipe 4 are attached to the suction- and pressure-ports respectively of said blower. The other end of the suction-pipe 3 is mounted on a nipple 5 of a valve-housing 6, fixed at a suitable point on the machine-frame 7. This housing 6 has other nipples 8 from which tubes 9 lead to the different connection-points 10 of the suction-elements. In the housing 6 a tubular valve 11 is rotatably mounted which has control-ports 12. The control-ports 12 are so arranged that 95 alternately the tubes 3 and 9 are made to communicate the one with the other or are shut off the one from the other after every quarter rotation of the rotary valve.

100 On the projecting end of an extension 13 of the rotary valve a control wheel or member 14 is keyed which carries a roller 15 at the end of each of its four arms and which is rotated each time 90° by a cam 17 fixed on a spur-wheel 16. The spur-wheel 16 is 105 rotated through the intermediary of a gear wheel 18 from a spur-wheel 20, keyed on a

shaft 19. The spur-wheel 16 has two cams 17 which are arranged in such a manner that, during one operation and one rotation of the spur-wheel 16, at a predetermined time the one cam establishes the communication between the pipes 3 and 9 and the other cam interrupts this communication again.

The pipe 4 for the blowing air is connected with a tubular-housing 21 in a similar manner, this housing being connected by flexible tubes 22 with the blowing air-nozzles. The wheel 23 of the rotary valve for the blowing air is controlled by two cams 24 on the toothed wheel 20 in a similar manner as the rotary valve for the suction-air.

Fig. 1 shows the elements in the position shortly before the lifting of a sheet. The sucker 25 rests already upon the top-sheet of 20 the pile 26. The one cam 24 will, shortly after this position, rotate the wheel 23 of the valve in the blowing air-conduit so that the communication between the elements 4 and 22 of this conduit is established, and 25 the one cam 17 of the spur wheel 16 will, immediately after this, rotate the wheel 14 of the suction-air-conduit so that the communication between the two conduit-elements 3 and 9 is established. When the top-sheet 30 has been lifted from the pile, the two other cams 22, 17 respectively shut off the communication between the blower and the blowing nozzles or suckers respectively.

In the form of construction illustrated in 35 Figs. 5 and 6 the control-cams for the suction air and for the blowing air are adjustably mounted on a common disk 28, which is provided with slots 27 receiving bolts or like fastenings securing the cams 40 17 and 24 thereto, the cams 24 controlling the blowing air being arranged on the front side of the disk, while the cams 17 controlling the suction-air are mounted on the rear side of said disk, i. e., said cams are thus 45 being disposed to operate in different rotary paths. The control wheels 14 and 23 respectively of the valves for the suction-air and for the blowing air are arranged so as to lie in the rotary paths of the cams 17 50 and 24 so as to be properly operated thereby.

A lifting cam 29 is further connected with

the disk 28 or keyed on the same shaft, said lifting cam 29 operating, by means of levers 30, 31, 32, the ratchet feed-gears 33, 34 which drive the conveying spindles 36 of the pile-table. All the control-elements, including the corresponding control-rigging, are arranged on that side of the machine on which the attendant stands so that they are easily accessible and may be adjusted

60 I claim:—

1. A pneumatic sheet-feeding mechanism for printing-presses, folding machines and the like, comprising in combination rotary valves for the suction air and for the blowing air, and cams for controlling said rotary valves.

2. In a pneumatic sheet-feeding mechanism as specified in claim 1, a rotary-blower for producing the sucking tension and the 70 blowing air.

3. In a pneumatic sheet-feeding mechanism as specified in claim 1, in combination with the rotary valves for the suction air and for the blowing air and with the controlling cams, a common shaft for said cams on which said cams are mounted displaced the one to the other in axial direction.

4. In a pneumatic sheet-feeding mechanism as specified in claim 1, in combination 80 with the rotary valves for the suction air and for the blowing air and with the controlling cams, a common shaft for said cams, a disk keyed on said shaft, and means for adjustably fixing on said disk the control-cams for the suction-air on one side of said disk and the control cams for the blowing air on the other side of said disk.

5. In a pneumatic sheet-feeding mechanism as specified in claim 1, in combination 90 with the rotary distributing valves for the suction air and for the blowing air and with the control cams, a common shaft for said cams on which said cams are mounted displaced the one to the other in axial direction, a pile-table, conveying spindles for said pile-table, a feed-gear for driving said conveying spindles, and a driving cam for said feed gear and keyed on said common shaft.

100 In testimony whereof I affix my signature.
GEORG SPIESS.
